UNITED STATES PATENT OFFICE

152,165

DESIGN FOR A WHIRLING TOY

John Merrico, Amelia, Ohio

Application January 21, 1947, Serial No. 136,268

Term of patent 14 years

(Cl. D34—15)

To all whom it may concern:

Be it known that I, John Merrico, a citizen of the United States, residing at Amelia, in the county of Clermont and State of Ohio, have invented a new, original, and ornamental Design for a Whirling Toy, of which the following is a specification, reference being had to the accompanying drawing, forming part thereof.

The figure is a perspective view of a whirling toy, showing my new design.

The appearance of the side of the toy not shown is substantially similar in ornamentation to the side illustrated.

I claim:

The ornamental design for a whirling toy, as shown and described.

JOHN MERRICO.
